UNITED STATES PATENT OFFICE.

EDMUND L. BULLOCK, OF HARTFORD, CONNECTICUT, ASSIGNOR OF TWO-THIRDS TO ELEAZER H. LYMAN AND ELIJAH PEMBER, OF SAME PLACE.

SWITCH-OPERATING ATTACHMENT FOR STREET-RAILWAY CARS.

SPECIFICATION forming part of Letters Patent No. 592,862, dated November 2, 1897.

Application filed July 20, 1897. Serial No. 645,260. (No model.)

To all whom it may concern:

Be it known that I, EDMUND L. BULLOCK, a citizen of the United States of America, residing at Hartford, in the county of Hartford 5 and State of Connecticut, have invented a certain new and useful Improvement in Switch-Operating Attachments for Street-Railway Cars, of which the following is a description, reference being had to the accompanying

drawings, wherein--

Figure 1 is a side elevation view with the parts in adjustment for holding the switch-operating tongue pointing straight ahead. Fig. 2 is a side elevation view with the parts 15 in adjustment which turn the switch-operating tongue to one side. Fig. 3 is a bottom end view of the switch-operating tongue and the tappet immediately appurtenant thereto. Fig. 4 is a plan view of the apparatus.

The object of the improvement is denoted 20 by its title. It is an attachment for a street-railway car which enables a man upon the car (an operator) to operate switch-tongues in the track without stopping the car or leaving 25 the same.

In the accompanying drawings the letter *a* denotes the floor or platform of the car and stands for the car as a whole, and *b* denotes some of the wheels for supporting the car.

The letter *c* denotes a switch-operating tongue, it being adapted to have lateral reciprocation. It is borne on and carried by the vertical shaft *d*, which is adapted for similar lateral reciprocation. This vertical 35 shaft is borne in and carried by the sleeve *e*, which has vertical reciprocation. Its top is formed into the cam *e'*, which co-operates with the cam-lugs *d'*, projecting from the vertical shaft *d*, so that when the sleeve is properly raised this cam and these cam-lugs co-operate to hold the switch-operating tongue *c* pointing straight ahead.

The letter *f* denotes a hand-lever for giving the sleeve *e* its vertical reciprocation. 45 The movement of this hand-lever is communicated to that sleeve through the connecting-rod *f'*, crank *f''*, shaft *f'''*, slotted arms *f''''*, and lugs *f'''''*, projecting from the sides of said sleeve. The letters *h* denote fingers projecting radially from said sleeve. On these are pivotally hung the links *i* in such fashion

that they may reciprocate laterally thereon. The letter *k* denotes the tongue-operating lever or tongue-lever, pivotally hung on one of these fingers. Its upper end is connected 55 to one arm of the bent lever *l*, which is pivotally hung in the link *l'*, which in turn is pivotally supported upon the support *l''* in such fashion that it can reciprocate laterally along with the links *i*. 60

The letter *m* denotes a connecting-rod running from one end of the bent lever *l* to a pivotal connection with the upper one of the fingers *h*.

It results from this construction just now 65 described that when the sleeve *e* is moved up and down the tongue-lever *k* is correspondingly vibrated back and forth.

The links *i* can be so adjusted laterally that the lower end of the tongue-lever will be in 70 front of the tappet *n*, as shown in Fig. 1, (when the sleeve *e* is raised,) or it can be thrown to either side of that tappet, so that when the tappet (with the appurtenant tongue *c*) descends the tappet and the tongue 75 are thrown to one side or the other, as desired, so as to operate the tongue of a switch in the track to one side or to the other.

The operation of the device has been pointed out in describing the construction of the 80 parts. By operating the hand-lever *f* the sleeve *e* can be moved up and down. When it is moved completely up, the switch-operating tongue *c* is held in the position pointing straight ahead. By operating the crank 85 *o* the tongue-lever *k* can be set to throw the switch-operating tongue *c* as it descends to one side or the other of its permissible lateral adjustment. The movement of the crank *o* is communicated to the links *i* through the 90 medium of the shaft *o'*, crank *o''*, and connecting-rod *o'''*. The lever *k* strikes one side or the other of the shoe end and causes said shoe to be deflected from its normal position.

I claim as my improvement—

1. In combination, the wheeled car, the switch-operating tongue, the vertical shaft carrying said tongue and bearing the cam-lugs, the cam-topped sleeve adapted for vertical reciprocation, the hand-lever for giving 100 said vertical reciprocation of said sleeve, and suitable intermediate means for communicat-

ing motion from said hand-lever to said sleeve, all substantially as described and for the purposes set forth.

2. In combination, the wheeled ear, the 5 switch-operating tongue, the vertical shaft bearing said tongue, the sleeve carrying said shaft and adapted for vertical reciprocation, the laterally-reciprocating links pivotally hung from said sleeve, the tongue-lever piv-

totally hung on one of said links, the bent lever pivotally hung on a suitable support, and the connecting-rod for operating said bent lever, all substantially as described and for the purposes set forth.

EDMUND L. BULLOCK.
